ENGINE STARTER

Herbert L. Meeder, Denver, Colo.

Application February 21, 1938, Serial No. 191,652

5 Claims.

(Cl. 74—9)

This invention relates to improvements in engine starters of the general type shown and claimed in U. S. Letters Patent No. 1,889,995, granted to me on December 6, 1932.

5 The type of engine starters to which the invention relates comprises a motor driven shaft that extends across a fly wheel whose outer periphery carries a ring gear. Attached to the shaft by means of a helical spring is a sleeve that is so mounted that it may rotate thereon. A pinion is attached to the sleeve by a threaded means that forces the pinion to move along the axis of the shaft whenever it rotates relative to the sleeve. The parts are so adjusted that the pinion is normally out of mesh with the ring gear but whenever the shaft and sleeve are suddenly rotated the inertia of the pinion prevents it from starting as quickly as the motor actuated shaft and sleeve and this lag produces a relative rotation of the pinion and the sleeve which results in an axial movement of the pinion that carries it into operative engagement with the ring gear.

If the pinion happens to engage the ring gear in such a way that its teeth can enter between those of the ring gear no trouble results but there is always an equal chance that the teeth of the pinion will strike the teeth of the ring gear; when this happens the forward movement of the pinion is stopped and the wedge action of the threaded connection forces the pinion against the ring gear teeth and stops the motor. We now have what is commonly called a "starter lock."

Many expedients have been tried and employed for the purpose of preventing the formation of such "starter locks", the most common expedient being the tapering of the pinion teeth.

One of the objects of this invention is to produce an engine starter, of the type indicated, that shall be of very simple and yet of substantial construction but which is composed of the minimum number of parts.

Another object is to produce a starter that can be constructed at a minimum of expense and which can be assembled and taken apart very easily.

A further object is to produce an engine starter that will automatically release itself if a starter lock is formed so that it will always operate even if the teeth on the pinion first strike the ends of the teeth on the ring gear.

A still further object is to produce an improved connecting means for the starter spring that permits the spring to be easily constructed and readily applied and removed.

55 Another object is to produce a spring and

means for attaching it to other parts of the device in such a way that there is no lost motion between the spring and the parts to which it is attached; and

Another object is to so construct the sleeve and the pinion that they can be connected and disconnected without the use of tools.

The above and any other objects that may become apparent as the description proceeds are attained by means of a construction and an arrangement of parts that will now be described in detail, reference for this purpose being had to the accompanying drawing in which the invention has been illustrated and in which:

Figure 1 is a longitudinal section through the assembly and shows the parts in their relative position when a starter lock has occurred and just before it is released.

Figure 2 is a view partly in section showing the manner in which the sleeve and the pinion are connected and disconnected;

Figure 3 is an end view of the sleeve shown in Fig. 2;

Figure 4 is a side elevation of the helical starter spring; and

Figure 5 is an end view of the spring.

In the drawing numeral 10 designates a drive shaft which is journaled in a bearing 11, that may be one bearing of the starter motor, which has not been shown. The shaft extends transversely of the fly wheel 12 which is provided with a ring gear 13 that has gear teeth 14. Attached to the shaft, adjacent the front end of the bearing 11 is a sleeve 15 having a flange 16. In the drawing the flange has been shown eccentric but it may be concentric with the shaft. The flange is preferably located at the middle point of the sleeve, but this is a matter of choice only. Sleeve 15 is secured to the shaft by means of a threaded pin 17 that extends beyond the outer surface and is perforated for the reception of a cotter pin 18 that engages the surface of the flange and holds the pin from rotating.

The flange is provided with a hole 19, to which reference will hereinafter be made.

Another and longer sleeve 20 is mounted on the shaft for relative rotary and longitudinal movement. This sleeve has an eccentric flange 21, similar to flange 16, which is provided with a hole 22.

A helical compression spring 23 is positioned between flanges 16 and 22 and this spring has its ends offset in the manner indicated in Fig. 4, from which it will be seen that near its ends the spring has been bent so that a portion marked 55

24 extends in the direction of the length of the spring. The length of the bent portion is slightly greater than the thickness of the flanges and when the parts are assembled, parts 24 are in the holes 19 and 22. The ends 25 of the spring are bent so that they are inclined towards the middle of the spring as indicated by dotted lines 26. When the sleeves 15 and 20 are detached from the shaft the ends of the spring can be inserted and removed from the openings in the flanges. When the sleeves are in place on the shaft the ends 25 engage the sides of the flanges and this puts the spring under a slight bending strain that prevents it from having lost motion with respect to the flanges.

15 In Fig. 1 the spring is shown fully compressed and in this position of the parts the adjacent ends of the sleeves are separated by a space *a*. When the parts are in normal inoperative position flange 20 21 occupies the dotted line position to the right of the full line position, the displacement represents the amount the spring has been compressed. In normal inoperative position the pin 27 is adjacent the other end of the slot 31.

25 It will be observed that sleeve 20 is longer than sleeve 15 and that the flange 21 is positioned closer to its inner end than to its outer end, in fact flanges 16 and 21 may be flush with the inner ends of the sleeves which are merely hubs. 30 However, since nothing is gained by positioning the flanges nearer the inner ends of the sleeves than that shown, that construction is preferred. Sleeve 20 extends a considerable distance towards the end of the shaft and is provided with a pin 35 27. The outer end of sleeve 20 is shorter on one side of a diameter than on the other and the shorter side is diametrically opposite from the pin.

A pinion 28, which is provided on one side with 40 an elongated hub 29, has a central opening of two different diameters, that portion to the left in the drawing has an opening of such size that it can receive the end of sleeve 20 and the outer end has an opening 30 of the same diameter as 45 the shaft 10. The hub 29 has a helical slot 31 through which pin 27 extends. The slot terminates near the inner end of the hub so that the hub can be applied to and removed from the sleeve by a movement like that illustrated in Fig. 50 2. After the hub 29 and sleeve 20 have been assembled on the shaft so as to form an assembly like that shown in Fig. 2 they are ready to function. If the hub is now rotated on the sleeve until a tooth on the pinion engages the 55 end of a tooth on the ring gear and if the shaft is then turned so as to produce further relative rotation between the sleeve and the hub the spring will be compressed until the parts assume the position shown in Fig. 2. If the pinion is 60 held against rotation and the sleeve rotated relative thereto the pin will soon reach the end of slot 31 and the resulting hammer blow will rotate the pinion relative to the ring gear and the spring will then project the pinion into operative position.

65 When the starting motor is started it produces a sudden turning of shaft 10 in the direction indicated by arrow 32 in Fig. 1. Since the pinion is free to turn on sleeve 20 its inertia will prevent it from rotating and this will produce 70 relative rotation between sleeve 20 and hub 29 with the result that the pin will move in slot 31 and force the pinion towards the ring gear. If the teeth of the pinion strike the spaces between the 75 teeth of the ring gear the parts will assume the

position indicated by dotted lines and the fly wheel will be turned, thereby "cranking" the engine. If, on the other hand, the teeth on the pinion strike the teeth on the ring gear, further outward movement of the pinion will be stopped 5 but sleeve 20 will continue to rotate and will move towards the left until the parts assume the position shown in Fig. 1. Upon further movement pin 27 strikes the left end of the slot, whereupon the hammer blow of the pin, assisted by the momentum of the rotating parts, will move the pinion relative to the ring gear until the teeth of the pinion reach the spaces between the teeth on the ring gear when the action of the spring, which is now under compression, will force the 15 pinion outwardly and into mesh with the ring gear. See dotted line position in Fig. 1.

Attention is called to the fact that to obtain the action just described, the adjacent ends of sleeves 15 and 20 must be free to move towards 20 each other a distance at least as great as the width of the pinion, and preferably as great as the maximum longitudinal movement of the pinion on sleeve 20, which distance is indicated by letter *b* in Fig. 1. It is apparent that if the 25 opposing ends of the sleeves come into engagement before the pin 27 reaches the end of slot 31, the parts will become firmly wedged and there can be no automatic release. By so proportioning the parts that the pin 27 reaches the 30 inner end of the slot before the sleeves come into contact with each other, the torque action exerted by pin 27 on the pinion will move the latter relative to the ring gear and cause it to be forced into mesh with the latter. This relationship of the parts is very important and results in an action that assures that any time the pinion teeth strike the ring gear teeth this will automatically be corrected, with the result that no starter lock will be formed.

40 In Fig. 1 the spring is shown fully compressed and the pin at the inner end of slot 31. Therefore, the hub can neither rotate nor move longitudinally outward on the sleeve but the two must now rotate together.

45 Attention is also directed to the extreme simplicity of the construction, to the ease with which the pinion can be detached from and connected with the sleeve and to the construction of the spring and its manner of attachment to the flanges.

50 The end of shaft 10 nearest the ring gear is considered as the outer end and whenever the terms "outer" and "inner" are employed they are used in this sense.

55 In the device illustrated the relative longitudinal movement of the pinion and sleeve 20 is substantially equal to the length of the teeth on the pinion, and the starter spring must be compressible a distance at least as great as the length of 60 the pinion teeth.

The slot 31 and pin 27 function in the manner of an ordinary thread to produce relative longitudinal movement when sleeve 20 and hub 29 rotate relative to each other. One important 65 difference however is that if ordinary threads were used some additional means would have to be provided to get the hammer blow effect that is produced when pin 27 strikes the inner end of slot 31. An equivalent means, may, of course, 70 be substituted for that shown and the pin and slot are merely illustrative of means for this purpose. It will be observed that the distance that sleeve 20 must travel in a direction to compress spring 23, after the outward movement of the 75

pinion is stopped by engagement of the teeth of the ring gear, depends on the length of slot 31 and its pitch because the release is effected by the sudden impact or hammer blow when pin 27 strikes the inner end of the slot. In actual practice distance b is slightly greater than the length of the pinion teeth plus necessary clearance but may be longer than this.

Having described the invention what is claimed as new is—

1. In an engine starter of the type in which a ring gear engaging pinion is connected with a power shaft by means of a sleeve attached to the shaft by a helical spring, the pinion and sleeve being interconnected by means comprising a helical slot, which is closed at its inner end, in one and a cooperating pin in the other, which produces relative longitudinal movement of the pinion and the sleeve whenever they rotate relative to each other, the sleeve being mounted for longitudinal movement on the shaft, in a direction to change the length of the spring, which movement in a direction to compress the spring is at least as great as the normal overlap of the teeth on the ring gear and the pinion.
2. In an engine starter having a power shaft, a sleeve carried thereby for rotary and longitudinal movement, a flange rigidly secured to the shaft, a helical spring having one end attached to the flange and the other to the sleeve, a pinion for engaging a ring gear, said pinion having an elongated hub, mounted on the sleeve for relative longitudinal and rotary movement, the hub having a helical slot which is closed at its inner end, a pin projecting radially from the sleeve and operatively engaged in the slot, whereby when the pinion is rotated relative to the hub it will also move axially thereon, the sleeve having an inward longitudinal movement on the shaft, from normal non-tension position of the spring to tensioned position, at least as great as the normal overlap of the teeth on the ring gear and the teeth of the pinion, whereby the sleeve can continue to rotate in the hub after the pinion has engaged the end of a tooth on the ring gear and ceased to move axially of the shaft, until the pin engages the end of the slot and effects a rotation of the pinion relative to the ring gear.
3. A motor driven engine starter for use with an engine having a gear connected therewith, which is rotated by the engine, a power driven shaft, parallel with the axis of the gear and extending transversely thereof, a flange non-rotatably attached to the shaft, a sleeve carried by
- the shaft and mounted for relative rotary and longitudinal movement thereon, said sleeve having a flange, a helical spring positioned between the flanges with its ends attached to the flanges, the sleeve extending beyond its flange on the side opposite from the spring, the end of the sleeve having a radial pin, a pinion having an elongated hub into which the sleeve projects, the hub having a helical slot for the reception of the pin, the parts being so proportioned and adjusted that when the spring is free from strain and the pinion is positioned as near as possible to the flange on the sleeve the outer end of the pinion will be spaced a short distance from the adjacent surface of the gear, the spring, the sleeve and the stationary flange will be so spaced that the spring can be compressed a distance at least as great as the distance the teeth on the pinion overlap as the teeth on the gear when the two are in operative engagement.
4. An engine starter of the type in which a driven pinion is projected along a shaft by means dependent on its inertia to move it into mesh with a starter gear carried by the engine, the starter comprising a power driven shaft, a flange attached to the shaft and held against movement relative thereto, a sleeve carried by the shaft for both rotary and longitudinal movement thereon, a flange integral with the sleeve, a helical coil spring enclosing the shaft, between the flanges, the spring having its ends attached to the flanges, the end of the sleeve opposite from the spring being shorter on one side of a diameter than on the other, a pin extending radially from the longer side, a pinion having an elongated hub, rotatably encircling to the sleeve, the hub having a helical slot for the reception of the pin, the parts being so proportioned that the spring can be compressed a distance slightly greater than the normal overlap of the teeth on the pinion and the starter gear.
5. A sub-combination of an engine starter comprising a sleeve having a flange at one end, the other end of the sleeve being shorter on one side of a diametrical plane than on the other, the longer side having a radial lug, a pinion having an elongated hub provided with a helical slot for the reception of the lug, the position of the slot, the length of the lug and the difference in the length of the sleeve on opposite sides of the diametrical plane being so proportioned that the sleeve can be inserted in and removed from the hub by a tilting movement.

HERBERT L. MEEDER.
